UNITED STATES PATENT OFFICE.

JAMES F. O'BRIEN, OF SEATTLE, WASHINGTON.

TOY VEHICLE.

Application filed March 15, 1926. Serial No. 94,745.

The present invention relates to that type of toy vehicle known as a mobile hobby horse and the fundamental object thereof is the provision of a manually propelled toy horse readily and quickly convertible from the wheeled type to the caterpillar type, or the reverse, whereby such toy horse may be used in the open air at all seasons and for propulsion upon any kind of surface under 5 the complete and positive braking and directional control of the operator at all times and at variable speeds as desired.

Contemplated by this invention is the provision of a mobile toy horse embodying improvements directed particularly to the several manually operable propelling mechanisms thereof, which include a propelling mechanism operable by the hobbling movements of the operator or rider acting upon 10 an oscillative saddle seat interconnected therewith, said mechanism embodying novel and noiseless ratchet mechanism to convert the oscillative movement of said saddle seat into continuous rotation of the driving 15 wheels of said horse; a propelling mechanism operable by downward pressure exerted by the operator upon reciprocative stirrups interconnected therewith, said mechanism also embodying novel and noiseless ratchet mechanism to convert the reciprocative movement of said stirrups into continuous rotation of the driving wheels of 20 said horse; novel steering mechanism for the horse; brake mechanism therefor; and novel caterpillar mechanism to propel the horse 25 upon snow, ice, or other slippery surfaces, all of which are important objects of my invention and are to be correlated in the broad aim of enhancing the efficiency of the device 30 for general use.

The above and additional objects which will hereinafter be more specifically treated, are attained by such means as are shown in the accompanying drawings, described in 35 the following specification and then more clearly pointed out in the claims, which are appended hereto and form part of this application.

With reference to the drawings wherein 40 is illustrated the preferred embodiment of the invention, with several modified forms thereof, and throughout the several views of which like characters of reference designate similar parts.

Figure 1 is a side elevation of the toy

horse comprehended by my present invention;

Fig. 2 is a top plan thereof;

Fig. 3 is a fragmentary longitudinal vertical section of the same taken through 3-3 60 of Fig. 2;

Figs. 4, 5 and 6 are transverse vertical sections taken through 4-4; 5-5; and 6-6, respectively, of Fig. 1;

Fig. 7 is a horizontal section taken 65 through 7-7 of Fig. 3;

Fig. 8 is a fragmentary transverse vertical section taken through 8-8 of Fig. 7;

Fig. 9 is a fragmentary longitudinal vertical section taken through 9-9 of Fig. 8; 70

Fig. 10 is a similar section taken through 10-10 of Fig. 7;

Fig. 11 is a side elevation of a modified form of toy horse;

Fig. 12 is a horizontal section taken 75 through 12-12 of Fig. 11;

Fig. 13 is a fragmentary longitudinal vertical section taken through 13-13 of Fig. 12;

Fig. 14 is a transverse vertical section 80 taken through 14-14 of Fig. 11;

Fig. 15 is a side elevation of another modified form of toy horse;

Fig. 16 is a horizontal section taken 85 through 16-16 of Fig. 15;

Fig. 17 is a fragmentary longitudinal vertical section taken through 17-17 of Fig. 16;

Fig. 18 is a vertical transverse section taken through 18-18 of Fig. 15;

Fig. 19 is a side elevation of still another 90 modified form of toy horse;

Fig. 20 is a horizontal section taken through 20-20 of Fig. 19;

Fig. 21 is a fragmentary longitudinal vertical section taken through 21-21 of Fig. 95 20; and

Figs. 22, 23 and 24 are fragmentary transverse vertical sections taken through 22-22; 23-23; and 24-24, respectively, of Fig. 19.

The numeral 25 designates a mobile toy horse having a hollow body 26, hollow fore and hind legs 27 and 28, respectively, and a head 29, all of which may be integrally fabricated from wood, magnesite (magnesium chloride) or any other suitable material. 100

An oscillative saddle seat 30 is hingedly connected at the forward end thereof by a hinge pin 31 to the withers 32 of the toy horse, and upon the underside adjacent the rear end is pivotally connected, by a de- 105 110

pending link 33 extending within the body 26, slotted thereat to accommodate the same, to the bifurcated rear end of a rearwardly extending ratchet lever 34 having a cylindrical casing 35 integrally formed upon the opposite or forward end thereof and concentrically mounted, or fulcrumed, thereat for independent oscillative movement upon a transversely disposed main shaft 36 journalled for rotation at the ends thereof within the side walls of the body 26, as shown more clearly in Figs. 5 and 7.

Splined or keyed to the main shaft 36 midway the length of the same is a drive gear 37 having integral ratchet wheels 38 and 39 formed upon the sides thereof, said ratchet wheel 38 being normally enclosed within and by the cylindrical casing 35. Interposed between the inner walls of the casing 35 and the teeth of the ratchet wheel 38 is a series of rollers or balls 40, which function as dogs therebetween to interlock the casing and wheel, when the ratchet lever 34 is moved in the direction indicated by the arrows in Figs. 3 and 9, whereby the drive gear 37 is intermittently rotated in the same general direction, and which function to unlock the casing from the ratchet wheel during the reverse and independent rotative movement of said casing upon said ratchet wheel, when the ratchet lever is moved in a direction opposite to that indicated.

The ratchet wheel 39 is enclosed in an identical manner and for a similar purpose by a cylindrical casing 41 formed upon the rear end of a forwardly extending ratchet lever 42 concentrically mounted, or fulcrumed, thereat for independent oscillative movement upon the main shaft 36. Rollers or balls 43 interposed between the teeth of the ratchet wheel 39 and the casing 41 serve and function to alternately interlock and unlock the casing and ratchet wheel during oscillative movement of the ratchet lever 42 in substantially the same manner, as hereinbefore described for the lever 34.

Set collars 44 fixedly secured upon the main shaft 36 serve to retain the ratchet levers 34 and 42 against axial movement upon said main shaft and function to maintain the correlated cylindrical casings thereof in normally abutting relation with the drive gear 37 and associated ratchet wheels thereof, substantially as illustrated in Fig. 8.

Reciprocal stirrup cables 45 are connected at the forward looped ends thereof to the bifurcated forward end of the ratchet lever 42 and extend upwardly and divergently therefrom to pass over guide sheaves 46, rotatively mounted upon the forward end wall of the body 26, from whence they extend rearwardly and divergently to pass through openings 47 formed in the upper side portions of said body, substantially midway the length thereof, wherefrom they ex-

tend downwardly and at their lower rear terminals are provided with reciprocal stirrups 48, of any well known form.

The ratchet levers 34 and 42 are of identical construction and are each provided with a helical compression spring 49 mounted upon an arcuate rod 50 fixedly secured at the upper end within the upper portion of the body 26, wherefrom said rod extends downwardly to pass through and slidably receive thereon the suitably apertured correlated lever thereof. The springs 49 serve to return the levers 34 and 42 to an inoperative position following each power stroke, and to minimize shock or undue wear upon the mechanisms associated therewith during the return strokes thereof resilient pads or cushions 51 are mounted upon the return terminals of the rods 50, all as substantially illustrated in Fig. 3.

Normally meshing with the drive gear 37 is a pinion 52 fixedly secured upon a transversely disposed counter-shaft 53 journalled for rotation at the ends thereof within the side walls of the body 26 below the main shaft 36 and in spaced parallel relation thereto. The counter-shaft 53 is connected by chain gearing 54 to a drive shaft 55 journalled for rotation at the ends thereof within the side walls of the rear portion of the body 26, which drive shaft is similarly connected by chain gearing 56 midway the length thereof to a rear axle shaft 57 journalled for rotation adjacent its outwardly projecting ends within the lower portion of the hind legs 28 of the toy horse and having rear driving wheels 58 fixedly secured upon said ends in any well known manner.

Mounted upon the drive shaft 55, in an obvious manner, is a brake mechanism 59, of well known form, connected by a forwardly extending articulated brake rod 60 to a pommel-shaped hand brake lever 61 pivotally mounted upon the hinge pin 31 and extending within the body 26 slotted thereat to accommodate the same.

The head 29 of the toy horse 25 is provided with a bridle 62, the bit portions of which are connected by reins 63 to the ends of an oscillative steering lever 64 fixedly secured midway its length upon a vertically disposed steering rod or shaft 65 adjacent the upper end thereof, which latter is journalled for oscillative movement in the forward upper portion of the body 26, while the lower end of said rod is journalled for similar movement within and projects downwardly through the transversely disposed lower portion or wall of the fore legs 27 of the said toy horse 25. Detachably secured upon the lower terminal of the steering rod 65 is a front axle 66 having front wheels 67 rotatively mounted upon the ends thereof.

The end portions of the oscillative steering lever 64 project or extend outwardly

through openings or slots 68 formed in the forward upper walls of the body 26 and to the terminals thereof are secured the forward looped ends of a steering rein 69, 5 which latter extends rearwardly to a point within convenient reach of the operator or rider of the toy horse 25.

To render the several propelling mechanisms and correlated parts thereof enclosed 10 within the body 26 readily accessible for assembly, repairs, or replacement the underside of said body is provided with a removable portion or section 70 normally and detachably secured to such body by screws 71, 15 as shown more clearly in Fig. 5.

With the operator or rider seated in the saddle 30 and with the feet of same supported in the reciprocative stirrups 48, the device is propelled forwardly by hobbling 20 movements of the body of said operator acting alternately upon the saddle 30 and the stirrups 48, causing alternate oscillative movements of the ratchet levers 34 and 42, whereby intermittent rotative movement is imparted to the drive gear 37 and substantially continuous rotary motion is imparted to the pinion 52 meshing therewith, which motion is imparted to the rear axle shaft 57 through and is geared up by the chain gearing 54 and 56 to rotate said rear axle shaft at a considerable greater speed than the said pinion 52, whereby the device is driven or propelled forwardly at reasonable speeds. The device is steered by the operator manipulating the steering rein 69 in an obvious manner.

In Figs. 11 to 14, inclusive, a mobile toy horse is illustrated, wherein a single propelling mechanism of a slightly modified form 40 and operable by an oscillative saddle seat is employed.

The numeral 72 designates the body of the horse, to the withers of which an oscillative saddle 73 is hingedly connected by a hinge pin 74. Integrally connected or otherwise fixedly secured to the underside of the saddle 73 adjacent the forward end thereof is a depending sector-shaped gear 75 extending within the body 72, slotted thereat 45 to accommodate the same, and normally meshing with a pinion 76 splined or keyed to a transversely disposed main shaft 77 journalled at the ends thereof for oscillation within the side walls of the body 72. Integrally formed with the pinion 76 is a chain sheave 78 to the periphery of which is connected the forward upper terminal of a reciprocative sprocket chain 79, wherefrom 50 said chain extends rearwardly to pass over an oscillative sprocket pinion 80 mounted for independent movement upon a drive shaft 81 journalled for rotation at the ends thereof within the side walls of the rear portion of the body 72. The sprocket chain 55 79 passes under said sprocket pinion 80 and

extends forwardly therefrom and at the forward lower end is connected by a retracting spring 82 to the forward wall of the body 72.

The oscillative sprocket pinion 80 is provided upon the inner side thereof with an integral inwardly projecting cylindrical casing 83 normally enclosing a ratchet wheel 84 integrally formed upon a sprocket wheel 85, both of which are splined or keyed to the drive shaft 81. Balls or rollers 86 interposed between the walls of the casing 83 and the teeth of the ratchet wheel 84 serve and function to alternately interlock and unlock said casing and wheel during oscillative movements of the casing, as will be manifest and apparent by referring to Fig. 13, wherein a portion of the casing 83, is broken away to disclose the relative disposition of the several parts of the ratchet mechanism. 80

Sprocket gearing 87 connects the drive shaft 81 to a rear axle shaft 88 journalled adjacent the outwardly projecting ends thereof within the lower portion of the hind legs of the horse and is provided upon such ends with rear driving wheels 89 fixedly secured thereto in an obvious manner. 90

The drive shaft 81 is provided with a brake mechanism designated generally by the numeral 90, which is fabricated in substantially the same manner, as the brake mechanism for the mobile toy horse 25, said mechanism 90 being connected to and controlled by a pommel-shaped brake lever 91 pivotally mounted upon the hinge pin 74 and extending within the body 72 slotted thereat for such purpose. 95

Steering gear designated generally by the numeral 92 is fabricated and mounted within and upon the forward portion of the body 72 in an identical manner and for a similar purpose, as hereinbefore described for the steering gear of the horse 25, said steering gear 92 including a front axle 93 detachably secured thereto having front wheels 94 rotatively mounted upon the ends thereof. 105

The horse is provided with depending stirrups 95 flexibly connected and secured in any well known manner to the body 72 substantially midway the length and adjacent the upper portion thereof, and is also provided upon the underside of the said body with a removable section 96 detachably secured thereon in the same manner and for the same purpose as hereinbefore set forth for the section 70 of the body 26. 110

With the operator seated in the saddle 73 and with the feet of same supported in the stirrups 95, the device is propelled forwardly by hobbling movements of the operator's body acting upon the said saddle 73 causing oscillative motion of the same and the correlated sector-shaped gear 75 thereof, which latter being in mesh with the pinion 76 concurrently rotates said pinion and the 120

chain sheave 78 interconnected therewith, in the general direction indicated by the arrow in Fig. 13, to thereby wind the sprocket chain 79 upon the sheave 78, whereat the 5 sprocket pinion 80 in mesh with the chain 79 is rotated with the integral cylindrical casing 83 thereof, in the direction aforesaid, whereupon the rollers 86 interlock the casing 83 with the ratchet wheel 84 to impart con- 10 tinuous rotative movement to the sprocket wheel 85, which movement is geared up by and is imparted to the rear axle shaft 88 by the chain gearing 87 to propel the device forwardly at a reasonable speed. Follow- 15 ing each power stroke of the saddle 73, the retracting spring 82 functions to reverse the movement of the sprocket pinion 80, chain 79, sheave 78, pinion 76, the sector-shaped gear 75 and the saddle 73, to return the same 20 to the retracted position illustrated in Fig. 13. During reverse movements of the sprocket pinion 80 and the correlated cylindrical casing 83 thereof the rollers 86 are seated within the roots of the teeth of the 25 ratchet wheel 84 to thereby unlock said cylindrical casing 83 from said ratchet wheel 84 and permit the cylindrical casing to rotate freely and independently thereon.

In Figs. 15 to 18, inclusive, a mobile toy 30 horse is illustrated, wherein a single propelling mechanism of a further modified form and operable by reciprocative stirrups is employed.

The numeral 97 designates the body of the 35 horse having a stationary saddle 98, which may be formed integral therewith, or otherwise fixedly secured thereto. Journalled at the ends thereof for oscillation within the side walls of the body 97 midway the length 40 of same is a transversely disposed main shaft 99 having a forwardly extending sector-shaped gear 100 fixedly secured thereto and normally meshing with a pinion 101 splined or keyed to a counter-shaft 102 journalled 45 for oscillation at the ends thereof within the side walls of the body 97 in spaced parallel relation to the main shaft 99 and adjacent the forward end of said body. Integrally formed with the pinion 101 is a chain sheave 50 103 to the periphery of which is connected the forward upper terminal of a reciprocative sprocket chain 104, wherefrom said chain extends rearwardly to pass over an oscillative sprocket pinion 105 mounted for 55 independent movement upon a drive shaft 106 journalled for rotation at the ends thereof within the side walls of the rear portion of the body 97. The sprocket chain 104 passes under and extends forwardly from 60 the sprocket pinion 105 and at the forward lower end is connected by a retracting or reversing spring 107 to the forward wall of the body 97.

A ratchet mechanism designated generally 65 by the numeral 108 and operable by the

sprocket pinion 105 is mounted upon and actuates the drive shaft 106, which is connected by geared up chain gearing 109 to a rear axle shaft 110 having rear driving wheels 111 fixedly secured upon the ends thereof. The construction and operation of the ratchet mechanism 108 is identical to that hereinbefore described for the modified form disclosed in Figs. 11 to 14, inclusive. 70

A brake mechanism of a type similar to that described for the mobile toy horse hereinbefore disclosed is designated generally by the numeral 112 and is operatively mounted upon the drive shaft 106, said mechanism being connected to and actuated by a pomme-shaped brake lever 113 pivotally mounted upon a hinge pin 114 adjacent the forward end of the saddle 98, as shown more clearly in Fig. 17. 75

The numeral 115 designates generally the steering gear of the horse, which includes a front axle 116 having front wheels 117 rotatively mounted upon the ends thereof, said steering gear being similar in construction and operation to that heretofore described for the horse 25. 80

Rigidly secured to the main shaft 99 adjacent the journalled ends thereof are forwardly and downwardly extending lever arms 118. Connected to the forward terminals of said lever arms 118 are the inner looped ends of reciprocative flexible stirrup cables 119, which extend upwardly therefrom and pass over sheaves 120, rotatively mounted upon the side walls of the body 97 midway the length thereof, from whence they pass through openings 121 formed in the said side wall thereof and extend downwardly from said openings 121 and at their lower ends are provided with reciprocative stirrups 122. 95

A removable section 123 detachably secured to the underside of the body 27 permits of ready access to the interior thereof. 100

With the operator seated in the saddle 98 and with the feet of the same supported in the reciprocative stirrups 122, the device is propelled forwardly by downward pressure exerted by the said operator upon the stirrups 122, which causes oscillation of the lever arms 118 and the correlated sector-shaped gear 100 thereof, which functions to actuate the mechanism associated therewith in the identical manner and for a similar purpose as that hereinbefore described for the sector-shaped gear 75. 105

In Figs. 19 to 24, inclusive, a mobile toy horse of the caterpillar type for use upon snow or ice is illustrated, wherein propelling mechanisms of still further modified forms and operable by an oscillative saddle seat and reciprocative stirrups, respectively, are employed. 110

The numeral 124 designates the body of the horse to the withers of which an oscillative saddle seat 125 is hingedly connected 115 125 130

by a hinge pin 126. Integrally or otherwise fixedly secured to the underside of the saddle seat 125 adjacent the forward end thereof is an offset and depending oscillative sec-
5 tor-shaped gear 127 extending within the body 124, slotted thereat to accommodate the same, and normally meshing with a pinion 128 mounted for independent oscillative movement upon a transversely disposed main
10 shaft 129 journalled for rotation at the ends thereof within the side walls of the body 124. The pinion 128 is connected with and actuates a ratchet mechanism 130, of the type hereinbefore described, which is opera-
15 tively connected to the main shaft 129 and similarly connected by geared up chain gearing 131 to a transversely disposed drive shaft 132 journalled for continuous rotation at the ends thereof within the side walls of
20 the rear portion of the body 124.

Journalled for oscillation at the ends thereof within the side walls of the body 124 at points thereon intermediate of and in spaced parallel relation to the main shaft 129 and drive shaft 132 is a transversely disposed shaft 133 having a forwardly and downwardly extending sector-shaped gear 134 fixedly secured thereto and normally meshing with a pinion 135 mounted for
25 independent oscillative movement upon the main shaft 129, which pinion is connected with and actuates a ratchet mechanism 136, similar in construction to the ratchet mechanism 130, and which is operatively connected to the main shaft 129, whereby the chain gearing 131 is alternately actuated by said ratchet mechanisms, to thereby continuously rotate the drive shaft 132.

Rigidly secured to the shaft 133 adjacent the journalled ends thereof are forwardly and downwardly extending lever arms 137 to the forward lower terminals of which are connected the inner looped ends of reciprocative flexible stirrup cables 138, which extend upwardly therefrom and pass through openings 139, formed in the upper portions of the side walls of the body 124 midway the length thereof, wherefrom they extend downwardly and at their lower ends are provided with reciprocative stirrups 140.

Retracting cables 141 having the forward ends thereof secured to and wound upon the oscillative casings of the ratchet mechanisms 130 and 136, respectively, and having the rear ends connected by retracting springs 142 to the rear end wall of the body 124, serve and function thereat to reverse the motion of the pinions 128 and 135 and retract the correlated sector-shaped gears 127 and 134 thereof following each power stroke of the latter, as will be manifest and apparent by referring to Figs. 20 and 21.

The drive shaft 132 is connected by geared up chain gearing 143 to a rear axle shaft 144 transversely disposed and jour-

nalled for rotation adjacent the outwardly projecting ends thereof within the lower portion of the hind legs of the horse and having driving sprocket wheels 145 fixedly secured upon said outwardly projecting ends.

Interposed between the side walls of the hind legs of the horse and the sprocket wheels 145 are forwardly extending side bars or caterpillar frame 146 having the rear ends thereof mounted upon the rear axle shaft 144 and the opposite or forward ends fixedly secured in any well known manner to the lower ends of the fore legs of said horse. Rotatively mounted upon the forward ends 80 of the bars 146 are sprocket wheels 147, which are connected by sprocket or caterpillar chains 148 having dogs 149 attached thereto and which are guided and maintained in proper spaced parallel relation 85 throughout the major portion of the length thereof by idler sprockets 150 rotatively mounted upon the upper and lower edges of the bars 146.

Detachably secured in spaced relation upon the underside of the hind legs of the horse are downwardly extending longitudinally disposed runners 151.

The numeral 152 designates generally a steering mechanism substantially similar in 95 construction and operation to the steering mechanisms hereinbefore shown and described, which includes a longitudinally disposed front runner 153 detachably secured thereto, as a substitute for the front axle 100 and wheels employed with the horse 25.

A brake mechanism 154 operatively mounted upon the drive shaft 132 is connected to and actuated by a pommel-shaped brake lever 155 pivotally mounted upon the 105 hinge pin 126, and functions in an identical manner to the brake mechanisms heretofore described.

The underside of the body 124 is provided with a removable section 156 detachably secured thereto for a similar purpose, as that described for the section 70 of the horse 25.

With the operator seated in the oscillative saddle 125 and with the feet of same supported in the reciprocative stirrups 140, the 115 device just described is propelled forwardly upon snow, ice, or other slippery surfaces by hobbling movements of the body of said operator acting alternately upon the saddle 125 and the stirrups 140 causing alternate 120 oscillations of the correlated sector-shaped gears 127 and 134 thereof and similar oscillations of the pinions 128 and 135 in mesh therewith, which latter oscillations are converted through the media of the ratchet mechanisms 130, 136, and the chain gearing 131 to continuous rotary motion at the drive 125 shaft 132, which motion is imparted by the chain gearing 143 to the rear axle shaft 144, whereby the caterpillar chains 148 are 130

actuated to propel the device in a forward direction.

From the foregoing description taken in connection with the accompanying drawings

5 it will be observed and noted, that the mobile toy horses herein disclosed are readily and quickly convertible from the wheeled type to the caterpillar type, or the reverse, whereby such mobile toy horses may be used in the 10 open at all seasons for propulsion upon any kind of surface and are at all times under the complete and positive control of the operators thereof.

While I have herein shown and described 15 the invention with sufficient detail to enable those skilled in the art to understand the mode of construction and the principles involved, it is to be understood that there is no intentional limitation herein to the specific form and precise details of construction 20 of the invention shown and described, except as expressly defined by the appended claims, and that various modifications of such construction may be resorted to without departing 25 from the invention or the benefits derivable therefrom. I also desire it to be understood that certain features of the invention herein shown and described may be employed in and with other combinations and 30 animals than those herein shown.

What I claim as my invention, and desire to secure by Letters Patent, is:—

1. In a toy vehicle, in combination, a mobile body, a manually operable oscillative seat 35 attached thereto, spring retracted ratchet propelling mechanism for said body interconnected with said seat for actuation there-

by, and manually operable flexible stirrups connected to said propelling mechanism for alternately actuating the same relative to the 40 seat actuation thereof.

2. In a toy vehicle, in combination, a mobile body, a manually oscillative spring retracted seat attached thereto, propelling mechanism for said body interconnected with 45 said seat for actuation thereby, and manually reciprocative spring retracted stirrups connected to said propelling mechanism for alternately actuating the same relative to the seat actuation thereof. 50

3. In a toy vehicle, in combination, a steerable mobile body, a manually operable seat mounted thereon, and caterpillar propelling mechanism for said body attached thereto and interconnected with said seat for 55 actuation thereby.

4. In a toy vehicle, in combination, a steerable mobile body, caterpillar propelling mechanism for said body attached thereto, and manually operable stirrups for actuating 60 said caterpillar propelling mechanism.

5. In a toy vehicle, in combination, a steerable and controlled mobile body, a manually operable seat mounted thereon, caterpillar propelling mechanism for said body 65 attached thereto and interconnected with said seat for actuation thereby, and manually operable stirrups connected to said caterpillar propelling mechanism for alternately actuating the same relative to the seat actuation thereof. 70

In testimony whereof I affix my signature.

JAMES F. O'BRIEN.
